UNITED STATES PATENT OFFICE.

EDWIN ALLEN GARDNER, OF CHICAGO, ILLINOIS.
STARTER FOR INTERNAL-COMBUSTION ENGINES.

Specification of Letters Patent. Patented Sept. 25, 1917.

1,241,206.

Application filed November 16, 1915. Serial No. 61,749.

To all whom it may concern:

Be it known that I, EDWIN ALLEN GARDNER, a citizen of the United States, residing at Chicago, in the county of Cook and State of Illinois, have invented a new and useful Improvement in Starters for Internal-Combustion Engines, of which the following is a specification.

My invention relates to improvements in spring starters for internal combustion engines, and my object is, in general, to improve the construction and increase the efficiency and utility of devices of this character. My spring starter is particularly designed for combination with internal combustion engines of the type used for driving motor vehicles, and with this service in mind I have so arranged the parts of the preferred construction of my invention as to make it lend itself most readily to such a combination. In the accompanying drawings, I have illustrated a preferred embodiment of my invention together with certain modifications of the same.

Referring to these drawings, Figure 1 is a side view of a preferred embodiment of my spring starter, partly in section and partly in elevation; Fig. 2 is a detail section taken on the line 2 of Fig. 1 and showing the rewind lever and its connection with the sliding shaft; Fig. 3 is an enlarged section on the line 3 of Fig. 1 and showing the starting clutch; Fig. 4 is a section on the line 4 of Fig. 1 showing my new form of coil clutch; Fig. 5 is a rear end elevation of the rewind counter-shaft and the clutch-releasing lever for the same; Fig. 6 is an enlarged longitudinal sectional view showing a modified form of rewind counter-shaft and clutch connections for the same; Fig. 7 is a view similar to Fig. 1 and showing a modified form of the starter designed to be applied as an integral part of the construction of the internal combustion engine; Fig. 8 is a broken detail section on the line 8 of Fig. 7; Fig. 9 is an enlarged vertical section through the central shaft of my starter, showing the coil clutch used for both the rewind and starting clutch; Fig. 10 is an enlarged section showing a modified construction of the coil clutch adapted for use as a starting clutch, Fig. 11 is a section on the line 11 of Fig. 10, and Fig. 12 is a diagrammatic side elevation of a complete engine having my starting device attached thereto.

For mounting my spring starter in co-operative relation with an internal combustion engine, I provide a bracket 20 (Fig. 1), which may be secured to the crank 60 case of the engine or the chassis frame of the vehicle in which the engine is mounted, as is most convenient, and in the embodiment of the invention shown in Fig. 1, preferably at the front end of the engine. 65 The bracket 20 supports the casing member or stationary housing of my spring starter which, as shown in the drawing, is of generally cup-shaped conformation, the closed end or bottom of the cup being secured to 70 the bracket 20 as by studs 22. The main shaft 23 of my starter passes centrally through the housing 21 and is supported by a collar 24 carried by or formed integrally with the bracket 20. Beyond this 75 collar 24 the shaft 23 is connected by the slideable coupling 23^a shown in Fig. 12 with the shaft 23^b of the internal combustion engine 23^c. Any method of connecting these shafts either directly or indirectly may be 80 employed, it being only essential that the shaft 23 may have a limited sliding movement as will later appear. Between the bracket collar 24 and the casing 21 the shaft 23 carries a flanged collar 25 pinned there- 85 to as shown at 25'. A helical compression spring 26 interposed between the bracket collar 24 and the shaft collar 25 constantly urges the shaft inward toward the casing 21. Within the casing 21 there is mounted a 90 sliding bearing bushing 27 which receives the shaft 23 within its internal bore and is splined as shown at 28 to slide freely without turning in the stationary casing 21. The bushing 27 carries at its outer end a flanged 95 head 29 between which and the collar 25 of the shaft 23 there is mounted a thrust bearing or washer 30. For shifting the bushing 27 and through it the shaft 23 against the force of the spring 26, there is provided a piv- 100 oted lever 31 mounted upon the casing 21 and having an apertured enlargement 32 intermediate its length (Fig. 2) for bearing against the rear face of the bushing head 29. The upper or free end of the lever 31 has 105 connected thereto an operating cable 33 which is connected with the foot pedal 23^a operating the clutch mechanism 23^c of the internal combustion engine, so that when the clutch is disengaged the cable 33 will be 110 pulled outwardly to rock the lever 31 and shift the shaft 23 to the left as viewed in

Fig. 1. As shown in the drawings the lever 31 is of relatively light construction and capable of being slightly flexed or bent under sufficient force so that by the application of such force the shaft 23 may be positively shifted inward without releasing the cable 33. Within an annular groove 34 in the inner face of the casing bottom and concentric with the shaft 23, there is mounted 10 a hub member 35 which extends outward beyond the casing 21 and in its outer portion bears upon the shaft 23 as shown at 36. Inward of the bearing portion 36 the hub 35 has a cylindrical clutch surface 37 which is adapted to coöperate with clutch rollers 38 which in turn coöperate with cam excrescences 39 which may be formed integrally upon the shaft 23. Between the head of the casing 21 and the clutch portion 37 the hub 20 35 is provided with internal screw threads 40 into which is threaded a traveling nut 41 which is held against rotation by a spline 42 in the bushing 27. The outer end of the nut 41 is adapted to bear against the inner end of the cam excrescences 39 on the shaft 23, for the purpose of shifting the shaft outwardly, a thrust bearing 43 being interposed 25 between the meeting surfaces of these parts.

The hub 35 is provided on its outer surface with a hook 44 (Fig. 3) which engages the inner end of the spirally-coiled spring 45, the outer end of this spring being secured to the inner face of the casing 21 by a similar hook, not shown. In order to rotate the hub 35 in a direction to coil or wind the spring 45, it is provided with a rewind gear 46 which lies outside of the casing 21 and serves to hold thereagainst a cover-plate 47. The rewind gear 46 has engagement with 30 a rewind pinion 48 formed integrally with or secured to a rewind counter-shaft 49 which is journaled in a boss 50 carried by the stationary casing 21. For driving the counter-shaft 49 there is secured thereon, 35 as by the threads shown in the drawing, a sprocket 51 which may be connected as by a chain 52 with a driving sprocket 53 which is journaled upon the outwardly extending portion 54 of the hub 35 and secured against longitudinal movement by a collar 55 suitably fastened to the hub. The driving sprocket 53 is formed as a part of or connected with a female clutch member 56 which lies concentric with the main shaft 50 23 and is adapted to coöperate with a male clutch member 57 which is pinned to this shaft, as shown at 58 in the drawings.

It is clear that if the rewind counter-shaft 49 were free to move in both directions, the 60 force of the spring 45, when the latter is coiled, would immediately drive the counter-shaft 49 and its connected driving clutch 56 in the reverse direction. It is therefore necessary to supply some means for preventing this reverse rotation of the shaft

49. The means adopted in the construction shown in Fig. 1, consists of a helically-coiled wire spring 59 which lies within an enlargement of the bore of the housing 50 and closely embraces the shaft 49. As shown 70 in the drawing, the wire of which the spring is constructed is preferably of rectangular cross-section tapering toward one end of the spring. This small or tapered end is caught in an aperture 60 of a releasing lever 61 75 which may be journaled directly upon the shaft 49 and secured against longitudinal movement as by a pin 62. The opposite end of the spring 59, which end is preferably circular in section, is led outwardly through 80 an aperture 63 in the boss 50 and secured thereto as by a nut 64 engaging its threaded extremity. The coil 59 constructed and mounted as described serves as a simple form of automatic one-way clutch or ratchet 85 stop to permit the counter-shaft 49 to be freely driven in one direction but to prevent its rotation in the opposite direction. The coil 59 accomplishes this purpose by virtue of the fact that it is so tightly wound upon 90 the shaft 49 as to frictionally engage the surface of the same. If, therefore, this shaft be driven in a counter-clockwise direction as viewed from its right-hand end in Fig. 1, the friction of the free end of the coil, 95 that is, the end secured to the release lever 61, will cause this end to be more tightly coiled upon the shaft. Such tighter coiling will bring about a greater frictional resistance which will, in turn, coil the spring 100 still more tightly, and in this way, as a matter of practice, the shaft 49 will become absolutely locked before it has turned any perceptible fraction of a revolution in the direction indicated. When, however, the shaft 105 49 is operated in the opposite direction, that is, in a clockwise direction, as viewed from the right-hand end in Fig. 1, the frictional engagement of the spring with the shaft will tend to uncoil or open the turns of the 110 spring, whereby they are released from their engagement with the shaft, and the shaft may then turn freely in the direction indicated. In order to release the spring 59 from its engagement with the shaft, the 115 release-lever 61 may be operated in a direction to uncoil the spring, whereby its frictional engagement with and locking action upon the shaft will be released.

In order to house or protect the projecting end of the shaft 23 and the clutch 57 carried thereby, I may provide a sheet-metal cover-plate 65 of appropriate form and adapted to be secured in any preferred manner to the stationary casing 21. For convenience in rewinding the spring 45 of my self-starter manually, I prefer to extend the counter-shaft 49 outwardly beyond the hollow boss 50 and to secure a pin 66 in this projecting end, whereby a crank or lever 120 125 130

may be conveniently applied for the manual operation of the counter-shaft.

Assuming that the various elements which make up my spring starter are in the position shown in Fig. 1 of the drawing, the male clutch member 57 being out of engagement with the female clutch 56 and the nut 41 screwed up to the left-hand end of the screw-threads 40, the main shaft 23 of the 10 starter which is connected with the crank-shaft of the internal-combustion engine may freely revolve in its bearings without affecting any other portion of the mechanism of the starter. This position of the starter last 15 described is the unwound position, and it will be assumed that while the starter is in this condition, the internal-combustion engine is operating under load. It is the customary practice to release the clutch mechanism of such engines, that is, to unload the 20 engine, before stopping the same. When, therefore, the operator of the engine desires to stop the same, he will first operate the clutch pedal 23^d to remove the load from the 25 engine. The cable 33 attached to the lever 31 of my self-starter being connected to this 30 clutch-operating mechanism so that the cable 33 is pulled at the time of disengagement of the clutch, the lever 31 will be rocked about its pivot and will operate upon the 35 head 29 of the bushing 27 to withdraw this bushing from the casing 21, thereby shifting the shaft 23 longitudinally in its bearings until the male clutch 57 engages the 40 female clutch 56, this shifting movement of the shaft 23 being permitted by its connections with the shaft of the internal combustion engine. The continued operation of 45 the internal combustion engine will drive the shaft 23 and through the clutch mechanism 56, 57 and sprocket and chain connections 53, 52, 51, will drive the rewind counter-shaft 49. The rewind pinion 48 of this 50 shaft being in engagement with the hub gear 46 will thereupon rotate this hub in a counter-clockwise direction, as viewed in Fig. 3, to coil up or wind the spring 45. It will be understood that this rotation of the hub 55 will be permitted by the roller clutch 35 connecting the same with the shaft 23. As the hub 35 revolves, the traveling nut 41 which is threaded therein will be moved to the right, as viewed in Fig. 1, the screw-threaded engagement between the hub and the nut being properly designed to effect 60 such movement, until at the time the spring 45 is completely rewound, the right-hand end of the nut 41 will engage the thrust bearing 43 and positively force the shaft 23 to the right as viewed in Fig. 1, thereby disengaging the clutch 57 from the clutch 56. Either the cable 33 or the lever 31 or some other portion of the mechanism connecting these 65 parts with the clutch of the internal combustion engine is designed to have sufficient

elasticity to permit of this shifting of the shaft 23. As soon as the clutch 57 has been disengaged from the rewind clutch 56, the hub 35 will come to rest, the spring being prevented from unwinding by reason of the 70 spring-lock 59 of the counter-shaft 49. The starter is now rewound and the internal combustion engine may be stopped. It will be understood that the normal rate of speed of an ordinary internal combustion engine 75 is so high that, in practice, the rewinding operation above described will be completed in the minutest interval of time and practically coincident with the disengagement of the clutch mechanism of the internal combustion engine, so that immediately after 80 such disengagement the engine may be stopped as in common practice.

When it is desired to start the engine, the release lever 61 will be oscillated in a counter-clockwise direction as viewed from the left-hand end of the shaft 49 in Fig. 1, whereby the locking coil 59 of the counter-shaft will be released from its engagement with the same. The force of the spring 45 85 acting upon the hub 35 will then cause the latter to revolve in a clockwise direction, as viewed in Fig. 3, whereby the rollers 38 are forced upwardly upon the cam excrescences 39 of the main shaft 23, and this latter shaft 90 is rotated in its normal or forward direction to start the internal combustion engine. During this clockwise rotation of the hub 35, the screw-threads 40 thereof will act to 95 retract or move the nut 41 to the left, so that when the spring is completely unwound this nut will again occupy the position shown in Fig. 1 of the drawing. This completes the cycle of operation of the starter.

In Fig. 6 I have illustrated a modification 105 of the re-wind counter-shaft and the method of mounting the same upon the casing. In this modification the casing 21 has a tubular boss 67 cast integrally therewith which receives and supports a stub-shaft 68 shouldered intermediate its length as at 69 and locked in position by means of a nut 70^a. The outwardly extending headed end 70 110 serves as a journal for a rewind pinion 71 and sprocket 72 which are preferably secured together as by the screw-threads shown in the drawing and correspond with the pinion 48 and sprocket 51 of the construction shown in Fig. 1. Beyond the sprocket 72 115 there is journaled upon the shaft end 70 a 120 brake pulley 73. Between an outer hub 74 of this brake pulley and a mating inner hub 75 formed on the sprocket 72, there are mounted clutch rollers 76, the two hubs and these rollers forming an automatic clutch of 125 the general type shown in Fig. 3. The brake pulley 73 is designed to have applied thereto any preferred form of friction brake, by means of which the pulley and consequently the sprocket 72 and rewind gear 71 may be 130

locked to prevent unwinding of the spring and may be released to permit the spring to unwind for the purpose of starting the motor.

- 5 In Figs. 7 and 8 of the drawings, I have illustrated a modification of my starter, this modification being designed to be applied in direct combination or connection with the clutch mechanism of the internal combustion engine. In these figures of the drawings, the numeral 77 designates the crank-shaft of the internal combustion engine, to the flanged head of which is secured a fly-wheel 78, the inner periphery of which forms a female clutch member. For coöperating with this clutch there is provided a male clutch member 79 which is pinned to the drive-shaft 80. This latter shaft is mounted for longitudinal movement in its bearings, its connections with the vehicle or other mechanism driven by the internal combustion engine being such as to permit of this longitudinal movement. For normally forcing the male clutch 79 into engagement with the fly-wheel 78, there is provided a helically-coiled clutch-spring 81 which bears at its outer end (not shown) against some portion of the frame, and at its inner end against a collar 82 pinned to the drive-shaft. Between this collar 82 and the fly-wheel 78, and around the drive shaft 80, I mount my spring starter. In general construction this form of spring starter is the same as that illustrated in Fig. 1. The stationary casing of my starter here designated 83 is of the same general form as that illustrated in Fig. 1, and is mounted in the frame by any preferred means (not shown). This casing 83 serves to support the pivoted end of a clutch-operating lever 84 which embraces the drive shaft 80 in the usual manner and is adapted to bear against the thrust collar 82 of the shaft in order to force the latter outwardly against the tension of the clutch spring 81. A connecting link 85 serves as a means by which the clutch lever may be operated from the customary foot pedal. In the modification shown in Fig. 7, the bushing 27 of the constructional form shown in Fig. 1 is omitted, the traveling nut 86 which corresponds to the nut 41 (Fig. 1) serving itself as a bearing for the shaft. This nut has a key-way 87 in which engages a tongue 88 carried by a locking key 89 suitably secured to the face of the casing 83. The nut 86 is threaded into a hub 90 corresponding to the hub 35 of Fig. 1 and between this hub and the shaft 80 there is mounted a roller clutch 91 of the same general form as that illustrated in Figs. 1 and 3. The outer end of the hub 90 carries a rewind sprocket and clutch member 92, which is journaled freely upon the hub, the clutch being a female clutch adapted to coöperate with a male clutch member 93 formed as an integral part

of or secured to the main clutch 79. A rewind countershaft 94 substantially identical with the shaft 49 of Fig. 1 carries a rewind sprocket and rewind pinion, the former being connected by a chain with the sprocket 70 92 and the latter engaging directly with the rewind gear formed upon the hub 90.

The operation of the form of starter shown in Figs. 7 and 8, is as follows: It will be noted that the clutch members 79, 93 are 75 so disposed that only one of them may be engaged at the same time, that is, when the shaft 80 is shifted to the extreme right, as viewed in Fig. 7, the clutch 79 will engage with the fly-wheel 78, while when the shaft 80 is shifted to the extreme left, the clutch 93 will engage with the rewind clutch 92, while in any intermediate position, both of these clutches will be free. It is therefore clear that the fly-wheel 78 can not furnish power 85 directly for operating the rewind clutch 92. This form of starter, therefore, is what I designate the inertia type, that is, it is designed to be operated by the inertia of the drive shaft 80 or of the vehicle or other 90 mechanism connected to this shaft at a time when the clutch 79 is out of engagement with the motor fly-wheel 78. Assuming that the motor to which the fly-wheel 78 is connected is in operation, and that the clutch 95 79 is in engagement, the drive shaft 80 and its connected mechanism will be revolving with the motor shaft. If the link 85 be then operated to shift the clutch lever 84 back against its collar 82 and withdraw the clutch 100 79 from engagement with the fly-wheel clutch-member the drive shaft 80 will continue to revolve for a limited time due to its own inertia and that of the mechanism to which it is connected, for instance, a motor 105 vehicle. If, during this time, the clutch lever 84 is moved sufficiently to shift the shaft 80 to its extreme outward position, the clutch 93 will engage the rewind clutch 92 thereby driving the rewind counter-shaft 94 and 110 through it the hub 90 to rewind the spring, as described in connection with the operation of the constructional form shown in Fig. 1. As the hub 90 revolves it will, by virtue of its screw-threaded connection, cause the 115 traveling nut 87 to move from its outer position as shown in Fig. 7, inwardly until it abuts against the cam excrescences of the clutch 91, whereby the drive-shaft 80 will be positively shifted inward against the force 120 of the clutch lever 84 to cause the clutch 93 to disengage from the rewind clutch 92. It will be understood that ordinarily the connecting link 85 of the clutch lever 84 will be connected directly to a foot pedal, and 125 that this pedal may yield against the force of the operator's foot to permit the inward shifting of the shaft 80. If, however the link 85 be connected to any positively locked mechanism, such as a ratchet-locking lever, 130

or the like, the lever 84 or its connection must yield to permit of this inward movement of the drive-shaft. The spring starter is now rewound and in condition to serve as a source of power for rotating the fly-wheel 78 and through it the internal combustion engine for starting the same. It will be understood that in this form of construction the clutch lever 84 must be allowed to move backwardly to permit the clutch 79 to engage the fly-wheel 78 when it is desired to start the motor.

In Figs. 9, 10 and 11, I have illustrated some modifications of the rewind clutch and starting clutch. In Fig. 9 the main shaft of the starter, designated 95, has a collar 96 formed thereon by which the shaft may be shifted to the right by the traveling nut 97, which corresponds to the nut 41 of Fig. 1, or the nut 86 of Fig. 7. This traveling nut 97 is threaded into a hub 98 and is prevented from rotating by the studs 99 with which the slotted ears 100 of the nut engage. In place of the roller clutch connecting the hub and the shaft, as shown in Figs. 1 and 7, I have shown in Fig. 9 a coiled wire similar to the counter-shaft clutches shown in Figs. 1 and 7. This coiled wire clutch, designated 101, has its end 102 secured to the hub 98 and its opposite end free and in frictional engagement with the shaft 95. It is clear that when the hub 98 turns in the direction indicated by the arrow in Fig. 9, the free end of the wire coil 101 will by its frictional engagement cause the coil to tighten upon the shaft 95 and eventually give a driving engagement with the same. When the hub 98 rotates in the opposite direction, however, the wire coil 40 will automatically loosen itself to permit the hub to turn free of the shaft.

For operating the rewind sprocket 102 of the construction shown in Fig. 9, I have provided a modification of the coiled wire clutch. In this modification the shaft 95 is surrounded by a bushing 103 which is splined to the shaft as shown at 104, to permit of the requisite longitudinal sliding of the shaft. The coiled wire, here designated 105, has its large end 106 turned outwardly and caught in a suitable aperture in the rewind sprocket 102 and has its small end turned forwardly and engaged in an aperture 107 in a male clutch member 108 mounted for rotation on the end of the rewind sprocket 102 and prevented from shifting longitudinally with respect thereto by the set-screws 109 which travel in the groove 110 turned in the cylindrical hub 55 portion of the sprocket 102. For coöperating with the male clutch 108, there is provided a female clutch member 111 rigidly secured to the shaft 95 as by a set-screw 112. The rewind sprocket 102 is held in 60 its proper assembled relation by a split col-

lar 113 fastened to the face of the rewind gear 114 of the hub 98 and bearing against a shoulder on the hub of the rewind sprocket.

The operation of the modified form of 70 rewind sprocket clutch shown in Fig. 9, is as follows: When the shaft 95 is shifted to the left by some suitable means as by the lever 31 of Fig. 1, or by the lever 84 of Fig. 7, the female clutch 111 which is secured to the shaft comes into engagement with the male clutch 108. Continued rotation of the shaft 95 therefore operates to turn the clutch member 108 and by its connection with the end of the spring 105 80 serves to forcibly tighten this spring upon the bushing 103, thereby causing the spring and bushing to become locked together. The bushing being keyed to the shaft 95 therefore drives through the spring directly 85 to the rewind sprocket 102, the sole function of the relatively small or light clutch members 108, 111, being therefore to maintain the spring 105 coiled tightly upon its bushing. When the clutch 111 is released 90 as by the inward shifting of the shaft 95, which is accomplished by the traveling nut 97 when the spring has been rewound, the clutch member 108 will thereby be freed, and the elasticity of the coil 105 will cause 95 it to unwind, thereby releasing the bushing 103 and permitting the sprocket 102 to come to rest. It should be noted that this form of construction differs from the coiled wire clutch hitherto described, in that the 100 coil 105 is so wound as to have a slight clearance upon its mandrel in place of having frictional engagement therewith as was necessary in the previously described forms of coil clutches. In the normal or un-stressed condition of the coil 105 therefore it is expanded clear of its bushing 103 and the latter may rotate in either direction without causing the coil to bind. It is only when, by operation of the clutch 108, the 110 coil is tightened upon the bushing that the automatic locking action takes place. While in Fig. 9 I have shown the clutch 108, 111 as being of the conventional cone or friction type, it will be readily understood that this 115 clutch might be of any approved design, such, for instance, as a roller clutch. In Fig. 10, I have shown such a roller clutch applied to the end of a coil 113 designed to replace the coil 101 shown in Fig. 9. The 120 main shaft, here designated 95', has formed thereon cam excrescences 114 which coöperate with rollers 115 and a sleeve or bushing 116 to form a complete roller clutch. The bushing 116 has a flange 117 formed 125 on one end in an aperture of which flange the free end 118 of the coil 113 is caught. The open end of the bushing 116 may be closed by a collar 119 suitably fastened to 130 the bushing and it is apparent that the

bushing 116 will serve to replace the fixed collar 96 on the shaft 95 of Fig. 9, so that the assembly represented by Fig. 10 may be placed bodily within the hub mechanism 5 of Fig. 9.

While I have shown and described in considerable detail several specific embodiments of my invention, it is to be understood that this showing and description is illustrative only and for the purpose of making my invention more clear, and that I do not regard the invention as limited to these details of construction or operation or to any of them, except in so far as I have included 10 such limitations within the terms of the following claims, in which it is my invention to claim all novelty inherent in my invention as broadly as is possible in view of the prior art.

20. What I claim as new and desire to secure by Letters Patent is:—

1. In a spring starter for internal combustion engines, a stationary housing, a 25 starter shaft connected with the engine and shiftable longitudinally, a spring surrounding the said shaft and having one end connected therewith and one end connected with the housing, means for rewinding the said spring from said shaft, a clutch for operating said rewind mechanism, and means operable by shifting movement of the shaft for controlling the said clutch.

2. The combination with an internal combustion engine and mechanism driven thereby of a clutch adapted to releasably connect the said engine and the said mechanism, a spring-starter housing member, a 30 starter shaft connected with the engine and shiftable longitudinally, a starter spring surrounding the shaft and having one end connected thereto and one end connected with the housing, means for rewinding the said spring from the said shaft, means operable by shifting movement of the shaft for controlling the said rewind mechanism, and connections between said clutch and said shaft for simultaneously moving the two.

3. In combination, an internal combustion engine, mechanism driven thereby, a clutch 35 interposed between the said engine and the said mechanism, a spring starting motor connected with the said engine, means for rewinding the spring of the said motor from the said engine, and connections whereby the movement of the said clutch controls the said rewind mechanism.

4. In combination, an internal combustion engine, mechanism driven thereby, a clutch 40 interposed between the said engine and the said mechanism, a spring-starting motor connected with the said engine, means for rewinding the spring of the said motor from the said engine, and means operable by disengagement of the said clutch for engaging 45 the said rewind mechanism.

5. In a spring starter for internal combustion engines, a stationary housing, a starter shaft connected with the engine and shiftable longitudinally, a spring surrounding the said shaft and having one end connected thereto and one end connected to said housing, rewind mechanism operable by rotation of said shaft for rewinding the said spring, means for shifting the said shaft in one direction to engage the said rewind mechanism, and means for shifting the said shaft in the opposite direction to disengage the said rewind mechanism.

6. In a spring starter for internal combustion engines, a stationary housing, a 80 starter shaft connected with the engine and shiftable longitudinally, a hub member upon the shaft, a clutch for releasably connecting said hub member and shaft, a spring surrounding the said shaft and having one end connected with the said hub member and one end connected with the housing, rewind gearing connecting the said shaft and hub for driving the latter in a direction opposite to that of the former, a clutch for operating 85 said rewind mechanism, and means operable by shifting movement of the shaft for controlling said rewind clutch.

7. The combination with an internal combustion engine and mechanism driven 90 thereby of a clutch interposed between said engine and said mechanism, a spring starter motor, a longitudinally shiftable shaft forming a connection between the said motor and the said engine, connections between the said 95 shaft and the spring of the said motor for rewinding the latter from the former, said connections being operable by shifting movement of the said shaft, and means for shifting the said shaft by a disengaging movement of the said clutch.

8. In a spring starter for internal combustion engines, a stationary housing, a 100 starter shaft connected with the engine and shiftable longitudinally, a hub member upon 105 the shaft, an automatic clutch adapted to releasably connect the hub member with the shaft, a spring surrounding the said shaft and having one end connected with the hub and one end connected with the housing, 110 rewind gearing connecting the shaft and hub for driving the latter in a direction opposite to that of the former, a clutch for operating 115 said rewind gearing, means operable by rotation of the hub for shifting the said shaft, 120 and means operable by the shifting movement of the shaft for disengaging said rewind clutch.

9. In a spring starter for internal combustion engines, a stationary housing, a 125 starter shaft connected with the engine and shiftable longitudinally with relation to the said housing, a hub member upon the shaft, an automatic clutch releasably connecting 130 the said hub member and shaft, a spring

surrounding the shaft and having one end connected therewith and the other end connected with the housing, rewind gearing connecting the shaft and hub for driving the latter in a direction opposite to that of the former, means operable by shifting movement of the shaft for disengaging said rewind gearing, and a traveling nut having screw-threaded connection with the said hub and adapted to effect such shifting movement of the shaft upon rotation of the said hub.

10. In a spring starter for internal combustion engines, a stationary housing, a starter shaft connected with the engine and shiftable longitudinally with relation to the said housing, a traveling nut surrounding the said shaft and adapted to shift the same, a hub surrounding the said shaft and having screw-threaded engagement with the said nut, a spring surrounding the said shaft and having one end connected with the said hub and one end connected with the housing, rewind gearing connecting the shaft and hub for driving the latter in a direction opposite to that of the former, an automatic one-way coil clutch for connecting the said shaft and hub, and a clutch for operating said rewind gearing, said clutch being operable by shifting movement of the said shaft.

11. In a spring starter for internal combustion engines, a stationary housing, a starter shaft connected with the engine, a hub member surrounding the said shaft, a spring interposed between said hub member and said housing, a clutch adapted to connect said hub and said shaft for driving the latter from the former by power of the said spring, a counter-shaft mounted parallel with said first-named shaft, a clutch for transmitting power from said shaft to said counter-shaft and from the latter to said hub for driving the latter in a direction to rewind the said spring, means for releasing said counter-shaft from said shaft, and an automatic clutch for locking the said counter-shaft against reverse rotation.

12. In a spring starter for internal com-

bustion engines, a stationary housing, a shaft arranged centrally therein and connected with the engine, a hub member surrounding the said shaft within the casing, a spring surrounding the said shaft and having one end connected with the hub member and one end connected with the housing, an automatic clutch for connecting the said hub and shaft to communicate power from the former to the latter, a counter-shaft mounted parallel with the said shaft, gear connections for driving from said shaft to said counter-shaft and from the latter to said hub for rewinding the spring, a releasable clutch mounted upon said shaft for driving said rewind gearing, an automatic clutch for locking said counter-shaft against reverse movement, and means for releasing said last-named clutch.

13. In a spring starter for internal combustion engines, a stationary housing, a starter shaft connected with the engine and shiftable longitudinally with relation to the said housing, a hub member upon the shaft, an automatic clutch connecting the hub member and shaft for driving from the former to the latter, a spring surrounding the said shaft and having one end connected to the said hub member and one end connected to the housing, a traveling nut having screw-threaded engagement with the said hub and splined to the said housing, connections between said nut and said shaft for shifting the latter from the former, a rewind counter-shaft mounted parallel with said shaft, driving connections between said shaft and said rewind counter-shaft and between the latter and said hub, means operable by shifting movement of the shaft for engaging and disengaging the said driving connections, an automatic clutch for preventing reverse rotation of said counter-shaft, and means for releasing said clutch.

EDWIN ALLEN GARDNER.
